UNITED STATES PATENT OFFICE.

CHARLES ADAMS, JR., OF CLIFFSIDE PARK, NEW JERSEY, ASSIGNOR OF ONE-HALF TO
SIDNEY F. WESTON, OF NEW YORK, N. Y.

SPRINKLER SYSTEM.

Application filed April 14, 1927. Serial No. 183,630.

This invention relates to fire extinguishing devices in general such as sprinkler systems and certain improved valves forming a part of such sprinkler systems.

5 Of the two types of sprinkler systems in general use today, the dry system is objectionable in that as a rule considerable time is lost, frequently as much as two to three minutes, after the fusible heads have been 10 opened in case of an emergency to permit the air disposed between the control valves and the fusible heads in the tubing to discharge before the fire extinguishing medium starts to discharge; and the wet system is 15 objectionable, especially in the colder climates, since the water located in the tubing disposed between the control valves and the fusible heads frequently congeals and freezes during the winter and thus this wet system 20 cannot be relied upon during cold weather.

This invention aims to overcome the objections aforesaid. To this end, the present invention has for an object to provide a system in which the medium contained in the 25 piping between the control valves and the fusible heads is a liquid having a low freezing point, a so-called non-freezing medium, which liquid at the same time does not support combustion and is itself non-com- 30 bustible.

More specifically, the invention further provides a valve particularly adapted for such systems whereby two mediums of different characteristics and different pressures may be effectively separated from one another while the system is at rest and until the emergency arises.

The invention also contemplates structural improvements in systems of this character, 40 and these and other features, capabilities and advantages of the invention will appear from the detail description of specific embodiments thereof illustrated in the accompanying drawings, in which

45 Figure 1 is a diagrammatic view of one type of system made according to the present invention;

Fig. 2 is a fragmental diagrammatic view of another type of system;

50 Fig. 3 is a sectional view of a valve forming a part of the present systems;

Fig. 4 is a detail sectional view of one of the automatic control valves.

In the embodiment illustrated in Fig. 1, 55 the roof of the building to be protected is

designated as A, and the ground line as B.

On the ground B, in the present instance, there is provided a fire pump 1, which is connected by the conduit 2 with the water supply. On the roof A, there is located the 60 frame 3 which supports the gravity or water storage tank 4, which has a supporting plate 5 by means of which and the frame 6 connected to the cylindrical wall of the tank 4, the tank 7 is properly supported extending 65 upwardly from the plate 5. The tank 7 is a closed tank, preferably sealed to prevent access to the interior thereof except by means of the conduit hereinafter described.

On the ground B, in the present instance, 70 there is also provided a second pump 8, generally smaller than the fire pump 1. This pump is connected to the water supply by means of the conduit 9, and is provided with a conduit 10 extending upwardly therefrom

75 to discharge into the tank 4 at the upper end thereof, whereby water may be supplied to the tank 4. On the ground B, in the present instance, there is also located a solution reservoir 11, which is connected to the conduit 9 by means of the conduit 12. The conduit 10 is connected to the bottom of the tank 7 by means of the conduit 13. The conduit 9 is provided with a globe valve 14 between its connection with the conduit 12 80 and the main source of water supply, and the conduit 12 is provided with a globe valve 15 between such connection and the tank 11. Similarly, the conduit 10 is provided with a globe valve 16 between its connection with the conduit 12 85 and the conduit 13 and the tank 4, and the conduit 13 is provided with a globe valve 17 between its connection with the conduit 10 and the tank 7.

When it is desired to pump water to the tank 4, it is only necessary to 90 shut off the globe valves 15 and 17 and open the globe valves 14 and 16, and on the other hand, when it is desired to pump the solution into the tank 7, it is only necessary to 95 shut off the globe valves 14 and 16 and open the globe valves 15 and 17.

The solution to be used must have a low 100 freezing point, at any rate much lower than the freezing point of water, and be incapable of supporting combustion and be non-com- 105 bustible itself. One medium which has given satisfactory results is a solution of calcium chloride.

In the present instance, a plurality of conduits 18 are provided, each of which is pro-

vided with a plurality of branch pipes 19 extending therefrom at different levels to indicate the several sprinkler branchways provided for the several floors in a building. 5 The discharge orifices (not shown) of the several branchways 19 are provided with fusible metal or caps in the usual way so that in case of emergency such fusible metal or caps, due to a rise in temperature, will 10 free the discharge orifices to permit the extinguishing medium to issue from the branchways 19.

In the present instance, the conduits 18 and branchways 19 are the piping or tubing located in the rooms of the building to be protected and which are filled with the initially discharging medium, in the present instance calcium chloride.

The conduit 13 is provided with the conduit 20 which is connected with the conduits 18 by the conduits 21, by means of which the non-freezing medium contained in the tank 7 may be supplied to the conduits 18 and branchways 19.

The tank 4 is provided with a conduit 22 extending from the bottom thereof down to the fire department connection 23, and the fire department connection is connected by means of the conduit 24 with the fire pump 1 and by means of the pilot valve 25 with the conduit 26, which conduit 26 in turn is provided with the several main control valves 27, 27. The main control valves 27, 27 are preferably provided, as illustrated, with the separation valves 28, 28 disposed adjacent thereto and between the main control valves 27 and the conduits 18.

The separation valves 28, 28, in the present instance, are provided to separate the non-freezing, initially discharging medium located in the tubing 18 and the branchways 19 from the water located in the conduits 26 and 22.

The separation valves 28, preferably as illustrated in Fig. 3, have an inclined annular recess 29 at the upper end of the branchway 30 of the conduit 26 to receive the ring 29' forming a seat for the closure member 31 to separate the medium disposed in the conduit 18 from the medium disposed in the branchway 30. The closure member 31 is preferably secured to a lever 32 hinged at 33 adjacent to the lower end of the annular recess 29. The closure member 31 has its lower face engaging the ring 29' to close the annular recess 35 in the ring 29', located on the annular recess 29 and forming the support for the closure member 31. The ring 29' is provided with an annular chamber 37 in communication with the annular recess 35, and communicating with the atmosphere by means of the orifice 38 registering with the opening 39 in the conduit 18. When the conduit 18 and branchway 30 is 65 empty, the closure member 31 will normally

rest on the ring 29'. After it is so closed, the system is preferably initially charged by first supplying the conduits 18 and branchways 19 with the non-freezing medium, the calcium chloride, and subjecting 70 such medium to a pressure greater than the pressure of the water, and thereupon allowing the water to pass the main control valves 27 to the branchways 30 below the closure members 31. An inexpensive and practical 75 way for raising the pressure of the medium over that of the water is by locating the medium supply tank 7 at a higher level than the level of the water supply tank 4 as shown in Fig. 4. Due to the greater pressure of the calcium chloride, the closure member 31 will be maintained in engagement with the ring 29' when the system is at rest, and be so maintained until the emergency arises when the fusible metal covering 80 the discharge orifices of the branchways 19 is destroyed and the calcium chloride permitted to issue therefrom, thereby relieving the pressure in the conduits 18, and at least lower the pressure of the medium above the closure members 31 below the pressure of the water contained in the branchways 30 to permit the water to open the closure members 31 and pass into the conduits 18 and branchways 19 to follow the calcium chloride 85 immediately in its passage through the branchways 19.

The recess 35 and annular chamber 37 cooperate in the present instance, to form an effective division or separation between the calcium chloride above the closure member 31 and the water below the closure member 31 so that the higher pressure of the calcium chloride may be maintained and at the same time the calcium chloride solution preserved 100 in its initially prepared degree of concentration. In other words, if a leak should be formed between the closure member 31 and ring 29', the opening 39 communicating to the atmosphere, the pressure in the chamber 37 will, of course, be lower than that of the water, and consequently the leakage of water from the branchways 30 will be dissipated in the chamber 37, before sufficient pressure can be created in the chamber 110 37 to force such water beyond the closure member 31 into the conduits 18. And similarly, any leakage of calcium chloride from the conduits 18 past the closure member 31 will be dissipated in such chamber 37 before sufficient pressure can be created in such chamber 37 to permit such calcium chloride to be forced beyond the closure member 31 into the branchways 30. 120

With this type of valve 28, the usual 125 alarm systems may be associated with the openings 39, and thus the valves 28 not only form a separation valve between a non-freezing medium at a certain pressure and water at a lower pressure, but also serve to operate such 130

alarm systems in the usual way, such for instance as illustrated in Patent No. 1,125,407 to E. F. Shipman.

When a large number of conduits 18 are provided to supply a corresponding large number of sprinkler branchways, it has in practice been found desirable to provide a valve substantially identical to the valves 28 for the pilot valve 25, such pilot valve 25, however, separating two columns of water as distinguished from the valves 28. As illustrated in Fig. 1, water passes through the valve 25 in a horizontal direction as distinguished from the valves 28 illustrated in Fig. 1 and the valves 28' illustrated in Fig. 2 in which, as illustrated, the water would pass in a vertical direction. The direction of the water is of course immaterial since the closure members 31, see Fig. 3, are maintained in closed position by pressure. For this reason, the valve 25 could be identical with the valves 28 or 28' such as illustrated in detail in Fig. 3.

It is of course obvious that the valve 59 should normally be maintained open to replenish the pressure of the medium in the branchways 18. On the other hand, in case of fire this valve 29 is intended to be closed by the pressure created by the water which is supplied through the conduit 60. When the valve 25 takes the form of the valve 28, see Fig. 3, the conduit 60 is provided with the drip valve 61, constantly to relieve the pressure of the water going from the conduit 22 to the closure member 31 as distinguished from the pressure of the water in the conduit 26 so that the closure member 31 will normally remain seated on the ring 29.

If instead of the embodiment illustrated in Fig. 1, the embodiment illustrated in Fig. 2 were used and all of the valves 28' were connected with the valve 59 by the bypass 60', it is obvious that the accumulated leakage from a number of the valves 28' might be sufficient to close the valve 59, as a result of which the medium pressure in the branchways could no longer be replenished and might in time decrease sufficiently to permit the closure members 31 in the valves 28' to open and thereby permit the water to mingle with the medium to defeat the purpose of the process.

The tank 7 is preferably provided at a considerable distance above the level of the roof in order to form the proper pressure. This tank 7 is also positioned above the level of the water in the tank 4 in order to increase the pressure in the calcium chloride as compared to that of the water, it being understood that the calcium chloride solution is heavier than water and would therefore create a higher pressure even if the tank 7 were located at the level of the tank 4. In order to take care of leakage, and at the same time provide against the free pas-

sage of the calcium chloride from the conduit 13 to the conduit 18 when the system is at rest, each of the conduits 21 is provided with an automatic control valve 40 similar to that illustrated in Fig. 4. The diaphragm 70 chamber 41 of this valve 40 has connected thereto the conduit 42, having a small inner orifice which connects with a conduit 18. Between the connection of the conduit 42 with the conduit 18 and the connection of the conduit 21 with the conduit 18, there is provided a gauge 43 to indicate the pressure contained in the conduit 18. The automatic control valve 40 is so regulated that the diaphragm 44 thereof will cooperate with 80 the pressure developed in the conduit 42 and the spring 45 to depress the plug 46 into position for shutting off communication through the conduit 21. The conduit 21, between the valve 40 and the conduit 18, has connected thereto a bypass 47 which connects with the conduit 21 between the valve 40 and the conduit 20. The valve 40 is so adjusted that it will shut off communication through the conduit 21 when the pressure 90 in the conduit 18 has been developed to a required point, a pressure equivalent to a column of calcium chloride extending above the highest point of the conduit 18. The calcium chloride may then continue to flow 95 from the tank 7 through the bypass 47 until it builds up a pressure in the conduit 18 equal to that coming from the tank 7, which pressure, however, is in excess of the water pressure in tank 4. When such pressure 100 has been developed in the conduit 18, the bypass 47 will so restrict the passage of the calcium chloride from the conduit 13 to the conduit 18 that the liquid will remain substantially at rest, and if anything, merely 105 take care of leakage that may occur in the branchways 19.

The tank 4 is provided with the usual overflow pipe 48.

The tank 7 is provided with a conduit 49 extending from the upper end of the tank 7 down through the bottom thereof and having a cap 50 formed at the bottom thereof.

The conduit 49 is provided to prevent the free circulation of air in the tank 7, the cap 50 being provided with oil or other suitable medium to seal the lower opening of the conduit 49. Such seal, however, is sufficiently weak to permit the admission of air should the emergency arise and the level of 120 the calcium chloride in the tank 7 begin to drop.

The conduit 22 is provided with a check valve 51 to prevent the passage of water into the tank 4 through such conduit 22 125 when the fire pump 1 is operating, but permitting the water in the tank 4 to pass down into the pilot valve 25.

When it is desired to shut off all of the conduits 18 for the purposes of repair, after 130

the medium has been discharged therefrom, it is only necessary to shut off the main valves 27 and the globe valve 52 provided in the conduit 13. When it is desired to shut 5 off only one conduit 18 and its connecting branches 19 for the purposes of repair and the like after the medium has been discharged therefrom, it is only necessary to shut off the globe valve 53, one being provided in each conduit 21 between the conduit 20 and the connection of the conduit 21 with the conduit 47.

The conduit 13 is connected with the conduit 26 by the short conduit 54, which is 15 provided with the globe valve 55. Communication between the conduit 26 and the conduit 13 may be rare and only when the small pump 8 is not working and it is desired to pump water into the tank 4 by 20 means of the fire pump 1. In other words, ordinarily the valve 55 will be set to shut off communication between the conduit 13 and the conduit 26.

After a fire, when it is desirable to restore 25 the sprinkler system to operative condition, it is only necessary to shut off the valve 52 and the valves 27 and open the valves 56 formed in the conduits 57. The conduits 57 connect the conduits 18 with the conduit 30 58, which in turn discharges into the tank 11. In such case, the tank 11 will serve as a reservoir to receive the solution of calcium chloride and water that may reside in the conduits 18 and branchways 19 after a fire.

35 For automatically shutting off communication between the conduit 13 and the conduits 18, the conduit 13 is provided with an automatic control valve 59, similar to the control valve 40, also provided, with a diaphragm chamber in its outer end which is connected by the conduit 60 having a small orifice with the pilot valve 25. The conduit 60 is provided with a small drip 61 to relieve pressure in the conduit 60, thereby in turn 45 to relieve the pressure in the conduit 22 when the pilot valve 25 is in closed position. The drip 61 will also serve as a warning drip to permit the discharge of calcium chloride if the valve 25 leaks. It is, of course, desired to prevent the leakage of calcium chloride into the city water main connected to the pipe 24. As a protection, the drip 61 is free to discharge such leakage of calcium chloride on the floor or other receiving surface 50 where it can be readily inspected and is intended to be readily inspected from time to time to indicate to the attendant that the calcium chloride is leaking back into the city water main. The operation of this automatic control valve 59 is such that in the event of a fire and the opening of a sprinkler branchway, or a serious break, which will discharge liquid from the system faster than the bypass 47 can supply pressure, the pressure 55 in the system will rapidly fall below

that which is exerted on the closure members 31 of the valves 28, whereby the valves 28 will open and admit water from the conduit 26 and in turn the pilot valve 25 will open and allow water to flow both into the system and through the conduit 60.

The water flow from the tank 4 and the conduit 22 or from the fire pump 1 or fire department connection 23 through the pilot valve 25, when issuing into the conduit 60, 70 will build up pressure faster than the drip 61 can dissipate it, and will thereupon develop sufficient pressure to close the valve 59, thereby cutting off passage of the calcium chloride from the conduit 13 into the conduit 20. Such valve 59 will remain closed as long as there is water flow through the system, in other words as long as the water pressure developed is sufficient to close the valve 59.

85 The operation of the device is briefly as follows:

When the system is empty, it is first necessary to fill the water tank 4 and the conduits 22 and 26. To this end, the main control valves 27 are closed and the valve 55 closed, the valves 15 and 17 also closed, and the valves 14 and 16 opened, whereupon the pump 8 is permitted to operate to pump water up through the conduit 9 to the conduit 10, and through the conduit 10 into the tank 4, until the proper level has been reached, at the same time permitting the water to pass down through the conduit 22 past the pilot valve 25 into the conduit 26 to the main control valves 27. It is then necessary to fill the tank 7 with the non-freezing mixture, in the present instance the calcium chloride solution. To this end, the valves 14 and 16 will now be closed, the valves 15 and 17 opened, the valve 52 opened, the valves 53 opened and the valves 56 closed. The tank 11 will be supplied with the calcium chloride solution, and thereupon the pump 8 operated to feed the calcium chloride solution through the conduit 12 into the conduit 13 to the tank 7 until the proper pressure has been developed. It is of course understood that the fusible caps for the discharge orifices of the sprinkler branchways 19 will then operate to close such orifices, and that the medium so pumped into the system will be supplied from the conduit 13 through the conduit 20 into the conduits 21 and therefrom into the conduits 18, until a predetermined pressure has been developed sufficient to close the valves 40, whereupon the medium will continue to pass from the conduits 21 through the bypasses 47 into the conduits 18 until the pressure in the conduits 18 substantially equals that developed in the tank 7. During this operation, it will be assumed that the closure members 31 on the valves 28 will rest on their respective seats 29, and the calcium chloride build up 90

90

95

100

105

110

115

120

125

130

such pressure above the closures 31. The pressure so built up will be in excess of the pressure built up in the tank 4, and consequently after the pressure in the conduits 5 18 equalizes the pressure in the tank 7, the control valves 27 may be opened to permit the water in the conduit 26 to flow up against the lower surface of the closure members 31. The closure members remain 10 closed since, as aforesaid, the pressure developed in the water will be less than that developed in the calcium chloride above the closure members 31.

The gauges 43 will indicate to the operator 15 when the pressure in the conduits 18 equals that in the tank 7, so that the valves 27 will, of course, not be opened until the desired pressure has been created in the conduits 18, and in turn, on the upper surfaces of the 20 closure members 31.

In the embodiment illustrated in Fig. 1, the pilot valve 25 will, of course, cooperate with the valves 28 to maintain the pressure of the water at the desired point below the 25 pressure of the calcium chloride, and thereby minimize the amount of leakage.

In the embodiment illustrated in Fig. 2, the pilot valve 25 is not used to control the automatic control valve 59, but instead 30 thereof, the automatic control valve is connected by the conduit 60' direct with the separation valve 28' similar to the separation valve 28 of the embodiment illustrated in Fig. 1. In this case, it is obvious that the 35 operation is practically the same, and that the automatic control valve 59 will be closed effectively as soon as the water is permitted to discharge through the valve 28', at which time sufficient pressure will be built up in 40 the conduit 60' to overcome the pressure dissipated by the drip 61' in the conduit 60'.

Similarly to the drip 61, the drip 61' will serve to cooperate with a receiving surface such as a floor or the like to permit the 45 discharge of the non-freezing medium such as calcium chloride onto the same when the valve 28' is defective, leaks or operates during a fire, and thus will indicate to the attendant such leakage. A non-freezing medium such as calcium chloride will produce 50 a wet spot on the floor that will not readily evaporate or dry up, exceeding by far the period required to dry up or evaporate a water spot. Consequently the average attendant should quickly detect such leak and 55 take steps to prevent the calcium chloride or the like from leaking back into the city water main.

It is obvious that various changes and 60 modifications may be made to the details of construction without departing from the general spirit of the invention set forth in the appended claims.

I claim:

65 1. In a system of the character described,

the combination with a sprinkler discharge branchway, of a water supply tank, a container for a non-freezing, non-combustible medium, a conduit connecting the water supply tank to said sprinkler discharge branchway, a second conduit for connecting said container to said sprinkler discharge branchway, means for causing said sprinkler discharge branchway to be filled with said medium, a separation valve for separating the water in said first conduit from the medium in said sprinkler discharge branchway, the medium being subjected to a greater pressure than the water and thereby causing 70 said separation valve to remain closed so long as such variation in pressure continues, a bypass connected to said sprinkler branchway, and an automatic control valve to obstruct the main passage to said sprinkler branchway after the required pressure has 75 been built up by the medium in said branchway, whereupon said bypass will function to replenish the system for leakage, said bypass also functioning to retard the passage of the medium to said sprinkler branchway 80 when said sprinkler branchway is open in case of fire thereby to facilitate the immediate reduction of the pressure in said medium to cause the separation valve to open 85 for the passage of the water. 90

2. In a system of the character described, the combination with a sprinkler discharge branchway, of a water supply tank, a container for a non-freezing, non-combustible medium, a conduit connecting the water supply tank to said sprinkler discharge branchway, a second conduit for connecting said container to said sprinkler discharge branchway, means for causing said sprinkler discharge branchway to be filled with said medium, a valve housing, an annular valve seat in said housing having an annular chamber emerging in its seat intermediate its inner and outer peripheries, a water control valve pivotally mounted in said housing and resting on said seat, an automatic control valve connected to said second conduit, and a tube connecting said annular chamber with said automatic control valve whereby the passage of water through said water control valve will cause said automatic control valve to obstruct passage of the medium through said second conduit and thus prevent the discharge of the medium after said water has begun to flow. 105

3. In a system of the character described, the combination with a sprinkler discharge branchway, of a conduit connected to supply a fire extinguishing medium to said sprinkler discharge branchway, a valve housing having a valve seat, a main control valve pivotally mounted in said housing and normally resting on said valve seat in closed position, an automatic control valve connected to said conduit, and a tube connecting said 110 115 120 125 130

valve housing with said automatic control valve through which, upon the opening of said main control valve and the passage of a medium through said main control valve, medium will be caused to flow to said automatic control valve, creating sufficient pressure to close the same and thereupon obstruct the passage of the medium through said conduit.

16 4. In a system of the character described, the combination with a sprinkler discharge branchway, of a conduit connected to supply a fire extinguishing medium to said sprinkler discharge branchway, a valve housing, an annular valve seat in said housing having an annular chamber in communication with the face of said seat intermediate the inner and outer peripheries of said seat, a medium control valve pivotally mounted in 20 said housing and normally resting on said seat, an automatic control valve connected to said conduit, and a tube connecting said annular chamber with said automatic control valve through which, upon the opening 25 of said medium control valve and the passage of medium through said medium control valve, medium will be caused to flow to said automatic control valve and create sufficient pressure to close the same and thereupon obstruct the passage of the medium through 30 said conduit.

5. In a system of the character described, the combination with a sprinkler discharge branchway, of a water supply tank, 35 a container for a non-freezing, non-combustible medium, a conduit connecting the water supply tank to said sprinkler discharge branchway, a second conduit for connecting said container to said sprinkler discharge 40 branchway, means for causing said sprinkler discharge branchway to be filled with said medium, a separation valve for separating the water in said water conduit from the medium in said sprinkler discharge branchway, 45 the medium being subjected to a greater pressure than the water and thereby causing said separation valve to remain closed so long as such variation in pressure continues, an annular valve seat for receiving said separation 50 valve and having an annular chamber emerging in its seat intermediate its inner and outer peripheries, said valve normally shutting off said annular chamber from access by the medium in said branchway and 55 the water in said water conduit, an automatic control valve connected to said second conduit, and a tube connecting said annular chamber with said automatic control valve, the opening of said sprinkler discharge 60 branchway in case of fire permitting said medium initially to discharge and at the same time relieve the pressure on said valve to permit the same to open for the passage of the water therethrough, the opening of 65 said separating valve in turn permitting the

access of the water to said tube to flow to said automatic control valve and shut off passage of medium through said second conduit to preserve the medium against discharge after the water has begun to flow.

70

6. In a system of the character described, the combination with a sprinkler discharge branchway, of a water supply tank, a container for a non-freezing, non-combustible medium, a conduit connecting the water supply tank to said sprinkler discharge branchway, a second conduit for connecting said container to said sprinkler discharge branchway, means for causing said sprinkler discharge branchway to be filled with said medium, a separation valve for separating the water in said first conduit from the medium in said sprinkler discharge branchway, the medium being subjected to a greater pressure than the water and thereby causing said separation valve to remain closed so long as such variation in pressure continues, a bypass connected to said sprinkler branchway, an automatic control valve to obstruct the main passage to said sprinkler branchway after the required pressure has been built up by the medium in said branchway, whereupon said bypass will function to replenish the system for leakage, said bypass also functioning to retard the passage of the medium to said sprinkler branchway when said sprinkler branchway is open in case of fire thereby to facilitate the immediate reduction of the pressure in said medium to cause the separation valve to open for the passage of the water, an annular valve seat for receiving said separation valve and having an annular chamber in communication with the face of said valve seat, said valve normally shutting off said annular chamber from access by the medium in said branchway and the water in said water conduit, a second automatic control valve connected to said second conduit, and a tube connecting said annular chamber with said automatic control valve, the opening of said separation valve also permitting the water to flow through said tube to said second automatic control valve and shut off the passage of the medium through said second conduit to preserve such medium against discharge after the water has begun to flow through said separation valve.

75

100 7. In a system of the character described, the combination with a sprinkler discharge branchway, of a water supply conduit connected to said sprinkler discharge branchway, a medium supply conduit also connected to said sprinkler discharge branchway, said medium conduit initially filling said sprinkler branchway with a non-freezing, non-combustible medium under a higher pressure than the pressure of the water, an automatic control valve connected to said medium conduit for obstructing the rapid passage of the medium through said sprinkler branchway

80

85

105

110

115

120

125

130

after the pressure has once been built up therein, and a separation valve for normally separating the medium from said water, the opening of said sprinkler branchway causing the medium initially to discharge therefrom and cooperate with said automatic control valve to diminish the pressure on said separation valve to a point below that of the water pressure thereby to permit the water to open said valve and follow the medium in its passage from said sprinkler branchway.

8. In a system of the character described, the combination with a sprinkler discharge branchway, of a water supply conduit connected to said sprinkler discharge branchway, a medium supply conduit also connected to said sprinkler discharge branchway, said medium conduit initially filling said sprinkler branchway with a non-freezing, non-combustible medium under a higher pressure than the pressure of the water, a separation valve for normally separating the medium from said water, a warning drip associated with said separation valve, and a receiving surface disposed adjacent to said drip to

receive the non-freezing medium being discharged to form a wet spot to indicate to the attendant that the separation valve is permitting the non-freezing medium to leak back into the water supply. 30

9. In a system of the character described, the combination with a sprinkler discharge branchway, of a water supply conduit connected to said sprinkler discharge branchway, a calcium chloride supply conduit also connected to said sprinkler discharge branchway, said calcium chloride conduit initially filling said sprinkler branchway with calcium chloride under a higher pressure than the pressure of the water, a separation valve 40 for normally separating the calcium chloride from said water, a warning drip associated with said separation valve, and a receiving surface disposed adjacent to said drip to receive the calcium chloride being discharged to form a wet spot to indicate to the attendant that the separation valve is permitting the calcium chloride to leak back into the water supply. 45

CHARLES ADAMS, JR.
